UNITED STATES PATENT OFFICE

EMIL TYDEN, OF HASTINGS, MICHIGAN

PISTON RING

Application filed February 28, 1932. Serial No. 595,258.

The purpose of this invention is to provide an improved piston ring suitable for use in an internal combustion engine, but not limited to such engine, adapted to be economically produced and to function for properly distributing the lubricating oil over the path of stroke of the piston in the cylinder, and to afford drainage for the surplus oil through the piston to the engine crank case. The invention consists in the elements and features of construction of the ring and the method of producing the same shown and described as indicated in the claims.

15. In the drawings:

Figure 1 is an axial section of an engine cylinder having a piston equipped with a ring embodying this invention.

Figure 2 is a plan view of one of the piston rings embodying the invention.

Figure 3 is an edge elevation of the same looking in the direction of the arrow 3 on Figure 2.

Figure 4 is a section at the plane indicated by the line 4-4 on Figure 3.

Figure 5 is a view similar to Figure 4 showing the drainage apertures reduced in dimension as compared with Figure 4.

Figures 6 and 7 are diagrammatic views 20 of mechanism which may be used in producing the ring shown in the preceding figures.

Figure 8 is an edge elevation looking in the direction of the arrow 8 on Figure 4.

Figure 9 is a view similar to Figure 4 of a modified form.

Figure 10 is a detail edge elevation of the form shown in Figure 10 looking in the direction of the arrow 10 on Figure 9.

Figure 11 is a detail edge elevation of the form shown in Figure 9 looking in the direction of the arrow 11 on Figure 9.

Before proceeding with description of the construction in detail to assist in the understanding of said construction and the purposes of the different details, the specific purposes of the invention may be set forth as follows:

A purpose of the invention embodied in 50 the ring shown in the drawings is to adapt

that ring to collect from the cylinder wall along which it is moved in the stroke of the piston, the lubricating oil which is supplied to the cylinder by the customary means, and to afford reservoirs in which the oil is carried by the ring for distribution over the cylinder wall in the piston stroke, and also to provide means by which oil in excess of that which is required for proper lubrication may be drained through or past the ring into the piston grooves, and thence through the drainage ports of the piston into the hollow piston cavity for passing back to the crank case.

In carrying out these primary purposes, the construction of the ring is designed to afford means for uniform distribution of the oil circumferentially of the ring and piston groove.

Another purpose of the invention is to provide a ring of desired rigidity, which is effected by having the outer walls tied together by a number of radially staggered bridges, or supports preventing the ring from collapsing or expanding, either through the strains set up in manufacturing, such as forcing a dull cutter into the metal and spreading the sides of the ring as happens when the cut is entirely through the wall of the ring or from the strains of friction on the cylinder walls as well as the expansion due to the heat of the motor.

A further purpose is to effect distribution of the breaking strain, due to spreading the ring in introducing it over the end of the piston, over a substantial arcuate extent of the ring, avoiding concentration of the strain at the point opposite the split.

A further and important purpose of the invention is to render the ring economical in production by customary shop methods.

For accomplishing these purposes, the ring indicated in its entirety by reference numeral, 30, is formed with a series of recesses, 31, which may be as shown, eight in number, cut in the outer circumference of the ring between the opposite transaxial faces of the ring, the consecutive recesses being spaced apart a short distance, as indicated at 33. These recesses made by saw out, as hereinafter

described, are in radial depth substantially less than the radial width of the ring and of uniform depth throughout their circumferential extent except that at the opposite ends 5 the bottom of the recesses are sloped outward radially due to the use of a revolving circular saw cutter by which the recess is cut.

In the inner circumference of the ring is formed a similar circumferential inner series 10 of recesses, 35, cut from the inner side and extending radially outward to a depth of at least equal to,—and preferably slightly more than,—the difference between the radial width of the ring and the depth of the first 15 mentioned recesses. These recesses, 35, similar to the recesses, 31, are of uniform depth throughout their circumferential extent, except that at the opposite ends the bottoms of the inner recesses are sloped radially inward 20 at the end portions, due to the use of the rotating cutter by which the recesses are cut.

The recesses, 35, of the inner series are positioned respectively radially opposite the intervals and partitions between the recesses, 25 31, of the outer series, and thereby in radially staggered relation; and each dimensioned circumferentially, that is, as to length, for lapping at opposite end portions on the proximate end portions of the adjacently consecutive recesses of the outer series.

It will be noted that by reason of the lapping upon each other of the end portions of the corresponding recesses of the two series, apertures seen at 36 are produced, through 25 which the recesses of the two series have flow communication with each other; and that by reason of the lapping described, with the communication apertures resulting at both ends of each of the recesses of both series, the 30 two series of recesses together constitute a completely continuous flow passage entirely around the ring, which serves the purpose of permitting the oil which may be abundant at one part of the circumference of the piston 35 and cylinder, and deficient at another part, to flow around the piston and to supply the deficiency. It will be noted that as shown in the drawings the extent of lap of each of the inner and outer recesses is relatively short, 40 so that the apertures are relatively restricted, thereby adapting the construction to operate limitedly for drainage of oil through the hollow piston to the crank case, while affording adequate facility for circulation around the 45 piston for equal distribution of the oil, as described.

The method of production of rings of the construction shown constituting part of the present invention will now be described.

50 The rings, 30, of suitable material dimensioned for being accommodated in the piston grooves, are first produced in the usual manner without the recesses described; and for forming these recesses, the ring, 30, may be 55 mounted fast on a mandrel, 40, and subjected

to the action of a rotating cutter, 41, which is mounted for being advanced radially against the outer circumference of the ring in a plane intermediate the planes of the opposite transaxial faces of the ring, the thickness of the cutter blade being to a substantial amount less than the thickness of the ring. The mandrel is arranged to be adjusted angularly about its axis to set the ring successively at the different positions suitable for exposing 70 toward the cutter blade successively the areas of its circumference which are to receive the circumferentially successive recesses respectively, the revolving cutter blade, 41, having its shaft, 42, journaled in an arm, 43, which is pivoted at 44 to an arm, 46, the latter arm being pivoted for swinging about the axis of the mandrel, 40, as indicated diagrammatically in Figure 6. To produce the recesses of the outer circumferential series, the operator at each angularly adjusted position of the mandrel and ring swings the cutter blade inward radially with respect to the mandrel and ring thereon to the proper distance for cutting the recesses of desired depth as described, and then swings the cutter-carrying arms, 43 and 46 about the mandrel axis through an arc for cutting the recesses of the desired arcuate extent, the line *a*—*a* 80 in Figure 4 showing the approximate path of 85 the center line of the cutter in relation to the ring.

For forming the recesses of the inner series, the ring may be mounted in a chuck or holder indicated by the carrying arm, 50, in Figure 7, said holder being mounted for adjustment angularly about its axis to position the ring at the several positions suitable for exposing the successive arcs of the inner circumference of the ring at which the recesses of the inner series are to be formed to the radial attack of the revolving cutter blade indicated at 51, which it may be understood is mounted for swinging outward for thus attacking the inner circumference of the ring, and forming the recesses of the inner series of the desired arcuate extent, the dotted line *b*—*b* in Figure 4 showing approximately the path of the center line of the cutter in relation to the ring.

Upon considering the operation of the piston ring constructed and mounted as described, it may be recognized that in the stroke of the piston, the recesses of the outer series will collect the oil scraped or wiped from the cylinder wall; and that the oil thus accumulated being free to pass from the recesses of the outer series into the successively adjacent recesses of the inner series, and from the latter to pass back into the next of the successively adjacent outer recesses, it results that thus the oil scraped from the cylinder wall at one side where the oil is abundant, may be transferred to any part of the cylinder wall where it is deficient.

And upon further consideration it may be recognized that some part of the oil which passes the apertures, 36, will remain in the recesses of the inner series, and thereby in the piston groove, and eventually may be drained out through the ports of the hollow piston into the crank case.

Upon further consideration it will be recognized that the apertures, 36, being rendered acute-edged by the sloping of the lapped end portions of the bottoms of the recesses of both series, the length of the flow passage which said apertures constitute, that is, its dimension in the direction of flow through the apertures, is practically zero, so that the liability of clogging of these apertures by their frictional detainment therein of solid particles, as of carbon or of other foul material, is rendered minimum and practically entirely avoided.

And the avoidance of this liability to clogging is the purpose of the sloping of the bottoms of the recesses as described by which the apertures are rendered acute-edged; and the liability of clogging is further reduced by these apertures being not at the inner circumference of the ring, but at a position leaving circumferential clearance between the apertures and the bottom of the piston grooves.

Upon considering the function of the piston ring for scraping or wiping the oil from the cylinder wall, it may be recognized that its efficiency for this function is promoted by the presence of the recesses of the outer series, these recesses being in width so large a fraction of the entire thickness of the ring that the lateral walls of the groove constituting peripheral circumferentially continuous flanges, as seen at 39 are quite thin and present thin edges for scraping or wiping the oil as described.

And upon this consideration it may be recognized as desirable that this feature of thin edges should characterize the entire circumference of the ring without interruption at any part, except where such interruption may be required in some cases to add strength to the ring, as for example and particularly at the point diametrically opposite the gap and at the ends at both sides of the gap.

For these reasons the ring is made, as shown in Figure 3, with the partitions, 33, between the consecutive recesses, 31, cut away at their outer circumferential ends to a very slight amount, as seen at 38, leaving standing only lateral portions which render the scraping edges of the ring circumferentially substantially continuous.

Upon considering the construction resulting from reducing the partitions as described so that there is flow communication between consecutive pockets over the radially outer end of the partitions, it will be recognized that by this means the pockets are rendered

component parts of a circumferentially continuous flow passage around the ring. In Figure 9 there is illustrated a modified form of the invention embodying this characteristic.

In this modification the outer series of recesses, indicated at 33^x, are identical in form and relation to each other with the recesses, 33, of the form shown in the previous figures, but the recesses, 35^x, of the inner series are less in radial depth than the difference between the radial width of the ring and the depth of the recesses, 33^x, of the outer series; so that the lapping past each other of the end portions of the respectively adjacent recesses of the two series does not create an aperture for flow communication between the lapped recesses. And accordingly in this form, Figure 9, the communication for flow radially of the ring in either direction is provided for by apertures indicated at 35^x, which are cut through the web left standing between the lapped portions of the outer and inner recesses respectively.

I claim:

1. A piston ring having an external circumferential series of recesses circumferentially spaced apart, each extending inwardly from the outer circumference of the ring to a depth substantially less than the radial width of the ring, and a second internal series of recesses extending from the inner circumference of the ring outwardly to a depth at least equal to the difference between the depth of the first mentioned recesses and the radial width of the ring, the individuals of said second series of recesses being circumferentially spaced apart successively and being each radially opposite the interval between two consecutive individual recesses of the first series and having their end portions lapping the end portions of said individuals of the first series, the recesses of both series having their bottoms at the opposite end portions thereof sloped and having the laps exceeding the length of the sloped portions and including a portion of the co-axially curved intermediate part of the bottoms of both series of recesses, whereby saidlapping portions constitute apertures through which the lapping recesses open into each other, and the ends of said apertures are rendered acute-edged and the radial extent of the apertures constituting flow passages intermediate the inner and outer circumferences of the ring is made substantially zero.

2. A piston ring having a series of external recesses each extending inwardly from the outer circumference of the ring a distance substantially less than the radial width of the ring and a series of spaced internal recesses each extending outwardly from the inner circumference of the ring a distance substantially less than the radial width of the ring disposed in alternating overlapping re-

lation to said external recesses, said internal and external recesses being connected at their ends by relatively small apertures disposed in substantially spaced relation to the inner edge of the ring, the portions of the edges of the ring between the recesses being beveled to thin edges.

3. A piston ring having a series of uniformly spaced external recesses each extending inwardly from the outer circumference of the ring a distance substantially less than the radial width of the ring, and a series of spaced internal recesses each extending outwardly from the inner circumference of the ring a distance substantially less than the radial width of the ring disposed in alternating overlapping relation to said external recesses, said internal and external recesses being connected at their ends by relatively small apertures disposed in substantially spaced relation to the inner edge of the ring.

4. A piston ring having a series of uniformly spaced external recesses each extending inwardly from the outer circumference of the ring a distance substantially less than the radial width of the ring connected by relatively shallow external grooves, and a series of spaced internal recesses each extending outwardly from the inner circumference of the ring a distance substantially less than the radial width of the ring disposed in alternating overlapping relation to said external recesses, said internal and external recesses being connected at their ends by relatively small apertures disposed in substantially spaced relation to the inner edge of the ring.

5. A piston ring for an internal combustion engine having an external circumferential series of consecutive recesses in the same transaxial plane between the opposite transaxially extending sides of the ring, the consecutive recesses of the series being circumferentially spaced apart from each other a relatively short distance by intervening partitions and having the opposite end portions of their bottoms sloped in a manner rendering the recesses deeper at the intermediate portions of their length, the depth at said intermediate portions being a substantial amount less than the radial width of the ring, the ring having an interior circumferential series of grooves in the same transaxial plane as the first mentioned series, each individual of the last mentioned series having its opposite end portions lapping proximate end portions of two consecutive recesses of the first mentioned series, the radial depth of the grooves of the last mentioned series being substantially less than the radial width of the ring and being at least equal to the difference between the radial depth of the recesses of the first series and the radial width of the ring, whereby the lapping of said recesses produces apertures through which the

recesses of both series have radial flow communication with each other, the ring being radially extended throughout its entire circumference at both transaxial sides slightly beyond the circumferential intervening partitions to form relatively thin-edged flanges at both sides for wiping the wall of the engine cylinder in the proper strokes of the piston.

In testimony whereof, I have hereunto set my hand at Hastings, Michigan, this 19th day of February, 1932.

EMIL TYDEN.
